UNITED STATES PATENT OFFICE.

GEORGE W. MCGILL, OF RIVERDALE, NEW YORK.

METALLIC FASTENER.

SPECIFICATION forming part of Letters Patent No. 337,969, dated March 16, 1886.

Application filed January 15, 1886. Serial No. 188,630. (No model.)

To all whom it may concern:

Be it known that I, GEORGE W. MCGILL, a citizen of the United States, residing at Riverdale, in the city and county of New York, State of New York, have invented a new and Improved Metallic Fastener, of which the following is a specification, reference being had to the accompanying drawings, making part of the same, and to the figures and letters of reference marked thereon, in which similar letters and figures of reference indicate corresponding parts.

My invention consists in a fastener made of a single piece of sheet metal, of greater length than width, shaped or fashioned to have a plate or disk at each end struck concavo-convex and connected together by a neck, one or both plates having a penetrating-prong extending from it.

In the accompanying drawings the device is represented embodied in three different forms, to wit: in the form of a pair of scallop-shells connected together by a neck integral therewith, as shown in Figures 1 to 8, inclusive; a scallop-shell and concavo-convex plate, similarly connected, as shown in Figs. 9 and 10, and as two concavo-convex plates similarly connected, as shown in Figs. 11, 12, and 13. Fig. 1 shows the blank from which the device is fashioned, struck up in scallop-shell form, 1 2 being the shells or plates, 3 their connecting-neck, and 4 the penetrating-prong of the device. Fig. 2 represents the blank so fashioned folded over on a line running across the center of the neck 3, with the concave surface of both plates or shells facing each other. Fig. 3 is a perspective view of Fig. 2, with the prong 4 bent out at an angle from the plate or shell with which it is connected, and both plates or shells facing each other at an angle. Fig. 4 represents a plan view of the fastener as applied in binding together several sheets of paper. Figs. 5 and 6 represent vertical sectional views of Fig. 4, taken on a line *xx* of that figure, Fig. 5 representing the position of the penetrating-prong 4 and covering plate or shell before being folded down on the opposite side of the papers, and Fig. 6 after being folded down. Fig. 7 is a view similar to Fig. 3, excepting that in Fig. 7 the prong 4 is shown folded in from the periphery of the plate or shell to form a shoulder, *b*, extending into the hollow of the same, and is then brought out at a right angle

from the concave surface of the shell or plate 5 on a line within the periphery of the same. Fig. 8 is a view similar to Fig. 6, showing the prong 4 fashioned as shown in Fig. 7. Fig. 9 is a view similar to Fig. 7, excepting that the plate 1 is given a dish form instead of a shell-form, and the prong 4, instead of being folded back into the hollow of the plate before being brought out at a right angle from the same, is cut to extend through the edge of the plate and is bent out at an angle directly from 65 the concave surface of the plate and on a line within its border or periphery. Fig. 10 is a view similar to Fig. 9, excepting that in Fig. 10 the prong 4 is represented fashioned wholly from the body part of the 70 plate 1, being cut as a tongue therein and terminating within the struck edge of the plate, and projecting out at right angles therefrom. Fig. 11 represents a modification in the struck-up blank of the device, wherein both 75 plates are provided with a penetrating-prong. Fig. 12 is a vertical sectional view of the fastener fashioned from the modified blank shown in Fig. 11, and applied in binding papers. Fig. 13 is a perspective view of the fastener 80 so fashioned; and Fig. 14 is a cross-section of the prong 4, taken on the line *yy* of Fig. 11.

The device proper is operated as follows: The penetrating prong 4 is forced through the papers to be bound until the periphery of 85 plate 1 rests on one side of the same at a distance from the margin to admit of the other plate, 2, being folded over on the other side of such papers, as shown in Fig. 5. The penetrating-prong 4 is then folded down on the 90 opposite side of the papers and toward the neck or hinge 3, and the plate 2 folded down over it, as shown in vertical sectional Fig. 6, thereby covering the prong and presenting similar convex surfaces on both sides of the 95 papers, as shown in Fig. 4. When the prong 4 is projected directly from the edge of the plate to which it is attached, as in Figs. from 1 to 6, inclusive, it is preferable to have the free plate 2 a little longer than the prong- 100 plate 1, as shown by dotted lines in Fig. 4, to admit of the plate 2 covering the whole of the folded part of the prong 4 and its point of penetration in the papers, to protect the latter and to admit of the edge of the plate 2 105 resting directly on the surface of one side of the papers, as does the edge of the other plate on the opposite side of the same. This end

may be accomplished by folding the neck 3 in manner to cause the front edge of the covering-plate 2 to project beyond the pronged edge of the lower plate. I prefer, however, to make both plates 1 and 2 of the same size, as shown in Fig. 7, and to accomplish the end above stated by folding the prong 4 back into the hollow or concavity of its plate before bending it out at a right angle from the same, 5 as shown in said figure. By this arrangement of the prong it will penetrate and leave the papers being bound at a point within the circumference of both of the plates 1 and 2, and admit of it and its point of puncture being 10 wholly covered by both plates, as shown in the vertical sectional Fig. 8. The fastener thus made, when applied, will present two convex surfaces rising from the papers or other articles which it binds—one on each side—with 15 their outer edge or periphery resting directly on the paper and covering the folded-over penetrating-prong and its point of puncture in the papers. A similar end may, in a measure, be accomplished by cutting the prong 20 into its plate through the edge of the latter, as shown in Fig. 9, or forming it wholly from the body part of the plate as a tongue, as 25 shown in Fig. 10, and projecting it at a right angle from its plate, as shown in both said 30 last-named figures.

The modification in the construction of the fastener shown in Figs. 11, 12, and 13 consists in providing both plates of the device with penetrating-prongs. These prongs are 35 cut integral with each plate and on parallel lines with each other, as shown in Fig. 11, and are folded back into their respective plates and out at right angles therefrom, as shown in Fig. 13. The papers or other articles 40 to be fastened have a slit punctured in them on a line parallel to their margin and at a proper distance therefrom, and of a length equal to the width of both prongs. Both prongs are inserted in this slit—one on opposite sides of the papers—and on the plates 45 12 being pressed together the prongs are forced through the papers, and on their points coming in contact with the concave faces of the plates they are deflected and forced down toward the papers, as shown in the vertical sectional Fig. 12.

The penetrating-prong 4 of the fastener, to increase its penetrating-power, may be made semi-cylindrical throughout its length, as 55 shown in Fig. 2, or struck with vertical ridges, as shown in Figs. 11, 13, and 14; and the neck 3 of the device may be similarly fashioned to increase its clamping-power, as shown at *a* in Figs. 1, 2, 11, and 13.

60 To cause the neck 3 to fold correctly on a line across its center, so as to bring the plates 1 2 to properly face each other, the neck may be weakened on that line by discontinuing one of the ridges *a* at the center point, as shown 65 in Fig. 11, or by providing the neck with a cross-slot or cross bead or ridge at that point.

It is manifest that the plates 1 and 2 may be struck concavo-convex, to represent various ornamental struck-up forms other than those herein shown, and also that the pronged 70 plate may be left flat and the unpronged or covering plate alone be struck concavo-convex to receive in its concavity the turned-down end of the applied prong 4, as before described.

What I claim as my invention, and desire to secure by Letters Patent, is—

1. A metallic fastener blank having a central part, 3, and plates 1 and 2, struck correspondingly concavo-convex, with a prong 80 or prongs, 4, projecting from the outer edge of one or both such plates, substantially as set forth.

2. A metallic fastener having two concavo-convex clamping-plates, 1 2, a penetrating 85 prong or prongs, 4, projecting from one or both of said plates, and a folded neck connecting such plates, as and for the purposes described.

3. In a metallic fastener having two connected clamping-plates, 1 2, the penetrating-prong 4, one or more, folded back on its connecting-plate to form the shoulder *b*, then out from said plate on a line within the border of the same, substantially as described. 90

4. In a metallic fastener having two concavo-convex clamping-plates, 1 2, connected together by an integral neck, 3, the penetrating-prong 4, one or more, arranged to project from within the border of its connecting-plate and at an angle therefrom, substantially 100 as and for the purposes described.

5. In a metallic fastener, a base-plate, 1, provided with a fastening-prong, 4, in combination with a covering-plate, 2, struck concavo-convex, and connected with and overlapping the base-plate by means of a folded connecting-neck, 3, made integral with both plates, the covering-plate adapted to receive in its concavity and cover the turned-down 110 point of the applied prong, as described.

6. In a metallic fastener having a base pronged plate and a concavo-convex covering-plate connected together by an integral neck, the penetrating-prong 4, cut wholly or partly from the body of the base-plate and bent up at an angle therefrom on a line within the outer edge or periphery of such plate, substantially as shown in Figs. 9 and 10, for the 115 purposes described.

7. A metallic fastener having two connected clamping-plates, 1 2, each plate provided with a penetrating-prong, 4, projecting from the outer edge of such plate on parallel lines with each other, as and for the purposes herein 125 set forth.

In testimony whereof I affix my signature in presence of two witnesses.

GEORGE W. McGILL.
